MANUFACTURE OF GASOLINE

Loren P. Scoville, Yonkers, N. Y., assignor to The
Texas Company, New York, N. Y., a corporation
of Delaware

Application January 15, 1943, Serial No. 472,439

1 Claim. (Cl. 260—683.1)

1

This invention relates to the manufacture of gasoline, such as aviation gasoline and motor fuel, from normally gaseous and liquid hydrocarbons. More particularly, the invention relates to the stabilization and fractionation of refinery hydrocarbon fractions, such as cracked naphtha and natural gasoline, and the catalytic conversion of effluent low-boiling or normally gaseous hydrocarbons to gasoline hydrocarbons of high anti-knock value.

One of the principal objects of the invention is to provide an improved process of stabilizing and fractionating petroleum products or fractions, such as cracked naphtha, and of converting low-boiling or normally gaseous effluents of such stabilization and fractionation to gasoline hydrocarbons of high anti-knock value, to thereby increase the yields of aviation gasoline and motor fuel produced from available refinery fractions, eliminate or minimize corrosion, and secure other advantages.

Another object of the invention is to provide a novel method of stabilizing and fractionating hydrocarbon mixtures to obtain a better separation of desired fractions, while at the same time providing a higher stabilization pressure and a greater overhead condensate recovery with available cooling water or other medium for the same reboiler temperature.

Still another object of the invention is to provide an improved method of stabilizing and fractionating hydrocarbon mixtures containing both paraffins and olefins of the same number of carbon atoms per molecule, whereby a portion of a normal paraffin may be retained in the stabilized bottoms for volatility while effecting a greater recovery of the olefins of the same carbon atom content in the overhead.

Another object of the invention is to provide an improved method of stabilizing raw cracked naphtha and polymerizing overhead low-boiling or normally gaseous unsaturated hydrocarbons to polymer gasoline, wherein a portion of a low-boiling normal paraffin is retained in the stabilized cracked naphtha for volatility, while at the same time a greater proportion of the olefins of the same carbon atom content as the low-boiling normal paraffin are removed in the overhead to thereby increase the yield of polymer gasoline.

2

Still another object of the invention is to provide an improved method of stabilizing raw cracked naphtha and natural gasoline, and alkyllating overhead low-boiling or normally gaseous isoparaffins with olefins to produce aviation gasoline, wherein a greater recovery of low-boiling olefins and isoparaffins is effected from the raw cracked naphtha and the natural gasoline to thereby materially increase the yield of aviation gasoline, while low-boiling normal paraffin components are retained in the stabilized naphtha or gasoline for volatility.

A further object of the invention is to provide apparatus for carrying out the method of this invention, which apparatus is simple in construction, is readily available and easily controlled, and economical in operation and maintenance.

Other objects and advantages of the invention will be apparent from the following description when taken in conjunction with the accompanying drawing and appended claim.

In the drawing which illustrates preferred embodiments of the invention:

Fig. 1 is a diagrammatic illustration of apparatus for carrying out the method of this invention as applied to the stabilization of raw cracked naphtha and the polymerization of effluent gases therefrom; and

Fig. 2 is a diagrammatic illustration of apparatus for carrying out the method of this invention as applied to a modification involving the stabilization and fractionation of raw cracked naphtha and natural gasoline, and the alkylation of effluent low-boiling or normally gaseous isoparaffins and olefins therefrom.

In conventional refinery practice, it is customary to stabilize raw cracked naphtha as obtained from the cracking of petroleum hydrocarbons to remove normal butane and lighter, the effluent gases then being treated and converted in part to gasoline hydrocarbons of high anti-knock value by various processes including polymerization and alkylation. The resulting conversion products are stabilized and fractionated to recover an aviation gasoline, and a portion of the normal butane may be blended back with the stabilized cracked naphtha for volatility. As applied to polymerization, it is customary to stabilize the raw cracked naphtha to remove over-

head C₄ and lighter. The overhead gases may then be fractionated to separate a selected C₄ fraction, and the resulting C₄ fraction is then polymerized to polymer gasoline, stabilized and hydrogenated to provide a saturated isoparaffinic aviation gasoline. On the other hand, the overhead gases may be condensed, and the condensate comprising mainly C₃—C₄ hydrocarbons polymerized and stabilized to form a high octane motor gasoline. In an effort to secure maximum yields of this gasoline, the raw cracked naphtha may be deeply stabilized to remove substantially all of the normal butane and lighter, so that practically all of the C₄ olefins are obtained in the overhead. In this operation, difficulties may be encountered in condensing the desired amount of overhead gases with the use of available cooling water without refrigeration due to the lower stabilizer pressure required for a given available reboiler temperature; and the increased yield of polymerizable olefins in the stabilizer overhead may be counterbalanced by the olefins remaining uncondensed and passing to the refinery gas lines, rather than being passed in the condensate to the polymerization unit. On the other hand, if the stabilizer pressure is maintained constant, this deep stabilization of the cracked naphtha requires a higher reboiler temperature, which may be above that normally obtainable with the available refinery high pressure steam supply. Also, the deep stabilization lowers the front end volatility of the stabilized cracked naphtha so that it will not meet specifications for motor fuel, and necessitates the blending back of normal butane with the stabilized cracked naphtha to meet front end volatility specifications.

Consequently, in many refineries, a compromise is effected on the basis of the available high pressure steam supply and the available cooling water temperature between the deep stabilization of the raw cracked naphtha described above and an operation in which a substantial proportion of the C₄ hydrocarbons are left in the stabilized cracked naphtha for volatility. While this latter operation retains normal butane in the stabilized cracked naphtha, it is also accompanied by a substantial loss of the C₄ olefins, particularly butylene-2, in the stabilizer bottoms. This results in a loss of desirable olefins in the polymer charge, with a resultant decrease in yield of aviation or motor gasoline from that theoretically possible from the available refinery stocks.

In order to operate at a sufficiently high stabilizer pressure to condense the major portion of the desirable constituents of the overhead from the raw cracked naphtha stabilizer, it has been previously proposed to inject water into the reboiler of the stabilizer. However, this method is necessarily limited to an increase in stabilizer pressure of approximately fifty pounds per square inch for a given reboiler temperature and, in addition, may result in increased corrosion.

In accordance with the present invention, an improved method of operation is provided for stabilizing the raw cracked naphtha directly to desired volatility and R. V. P., while at the same time the portion of C₄ retained in the stabilizer bottoms consists largely of normal butane, and a materially increased proportion of C₄ olefins for the particular relatively low reboiler temperature used is secured in the overhead. Moreover, this method at the same time enables the stabilizer operating pressure to be increased substantially more than the above-noted fifty pounds for a

given reboiler temperature without the use of water injection, whereby an increased recovery of the valuable unsaturated hydrocarbons is obtained in the overhead condensate by the use of available cooling water, or the same recovery can be obtained with a reduced overhead condenser surface area. This is accomplished by injecting into the stabilizer an essentially saturated hydrocarbon fraction, such as a butane fraction, which is heavier than the overhead from the stabilizer but is lighter than the average of the heavier stabilized fraction removed as bottoms. This injected hydrocarbon fraction may be obtained from an external source, but preferably is obtained as a product of the stabilization and fractionation of the resulting polymerization products from which unsaturated hydrocarbons or olefins have been essentially removed. The injected hydrocarbon fraction may be introduced at any point within the tower below the point of entry of the normal reflux condensate, but preferably is added below the point of entry of raw cracked naphtha charge. Very good results have been secured by introducing this saturated C₄ recycle stream into the stabilizer reboiler.

The invention is more particularly illustrated in Fig. 1, which shows the raw cracked naphtha as obtained from a refinery cracking operation being charged by pump 10 through line 11 into an intermediate point of stabilizer 12. The latter may be a conventional fractionating tower of the multiple bubble plate type, and is equipped with a line 13 for withdrawing liquid from a pool within the base of the tower and passing the same through a reboiler 14 heated by high pressure steam supplied to heating coil 15, the heated hydrocarbon being returned to the base of the tower by line 16. A bottoms of stabilized cracked naphtha is withdrawn from the base of the tower by line 17. Overhead gases composed of C₄ and lighter pass by line 18 to water-cooled condenser 19 and thence by rundown line 20 to accumulator 21. Uncondensed gas, mainly C₂ and lighter, is bled off from accumulator 21 by overhead line 22 to suitable gas-collecting means not shown. Liquid condensate, consisting largely of C₃—C₄ is withdrawn from the accumulator through line 23 and forced by pump 24 through line 25. The latter communicates with branched lines so that a portion of the condensate may be returned by line 27 to the upper portion of tower 12 to serve as reflux therein, while another portion passes by line 28 to a polymerization unit indicated generally at 29.

Any conventional catalytic or thermal polymerization unit for converting the olefinic constituents of the charge to polymer may be employed. Since the polymerization unit per se forms no part of the present invention, further illustration thereof is deemed unnecessary. By way of example, the unit 29 may be a conventional phosphoric acid unit provided with a heater in which the charge is raised to a temperature of about 350–500° F. and then passed through a catalytic tower or converter containing kieselguhr on which is absorbed the phosphoric acid catalyst. The operation thus far described is a so-called non-selective polymerization in which both C₃ and C₄ olefins are polymerized in the presence of each other. However, it is to be understood that the overhead condensate from the stabilizer 12 could be further fractionated to separate mainly a C₄ fraction, whereby cross-polymerization of normal and isobutylenes occurs in the unit 29. In any event, it is to be understood that

the C₄ olefins of the charge are largely consumed in the polymerization step to form higher boiling normally liquid polymers.

The resulting polymerization products are passed by line 30 to a depropanizer 31 where C₃ and lighter are removed overhead by line 32 and the depropanized polymer gasoline is withdrawn as bottoms by line 33. The overhead gas passes to condenser 34 and thence by rundown line 35 to an accumulator 36 from which condensate is withdrawn by line 37 and returned by pump 38 through line 39 to an upper portion of tower 31 to serve as reflux therein. It is also to be understood that the depropanizer 31 may be equipped with a suitable heating coil or reboiler in the conventional manner.

The depropanized polymer gasoline passes by line 33 into a debutanizer 40 also equipped with a conventional heating coil or reboiler at the base of the tower (not shown), and from which a saturated C₄ stream consisting essentially of normal butane and isobutane is removed as overhead by line 41 and a stabilized polymer gasoline is withdrawn as bottoms by line 42 for passage to motor gasoline storage or to a hydrogenator (not shown) in the case of selective polymerization in the production of aviation gasoline as is well understood. The saturated C₄ gases pass by line 41 to condenser 43 and run down line 44 to an accumulator 45. The saturated C₄ condensate is withdrawn from accumulator 45 by line 46 and forced by pump 47 in part through line 48 to the top of tower 49 to serve as reflux therein, and in part by line 49 to the reboiler 14 of cracked naphtha stabilizer 12.

The amount of saturated C₄ which is recycled through line 49 to stabilizer 12 can be varied within substantial limits. For example, a relatively small amount of recycle on the basis of the raw cracked naphtha charged will give improved operation, and this can be varied up to the recycle of substantially all of the saturated C₄ condensate not required as reflux in debutanizer 40. Thus, a recycle rate of as little as one part by volume of saturated C₄ to a hundred parts by volume of raw cracked naphtha charged and up to equal parts by volume or more may be employed. In the latter case, it is obvious that additional saturated C₄ from an external source would be required in initiating operation and until there had been substantial buildup of the saturated C₄ in the system. Generally, about one part of saturated C₄ to twenty parts by volume of raw cracked naphtha charged up to one part of recycle to ten parts of naphtha charged are preferred to maintain the proper balance in the system. It will be understood that this will vary for different reboiler temperatures and different temperatures of available cooling water and can readily be determined in actual operation by those skilled in this art for the particular conditions encountered to provide the most efficient operating conditions. In operation, the amount of recycle may be controlled by any conventional rate of flow controller in accordance with the rate of feed of the raw cracked naphtha to stabilizer 12. This is illustrated diagrammatically by ratio flow controller 50 between line 11 and line 49 with air connection 51 regulating a valve 52 in recycle line 49. It is to be understood that the hydrocarbon recycle can also be combined with direct water injection into the stabilizer tower, if desired, to obtain the cumulative effect on increase in tower pressure for a given reboiler temperature of both the hydrocarbon injection and the water injection.

The following results were obtained in comparative runs in commercial operation on a combined raw cracked naphtha stabilization operation and a polymerization of the stabilizer overhead condensate by a conventional phosphoric acid polymerization process. In one run, the raw cracked naphtha stabilizer was operated in conventional manner without hydrocarbon recycle and injection into the reboiler of the stabilizer. In another run, a saturated C₄ fraction obtained in the stabilization of the polymerization products as in Fig. 1 above was recycled at the rate of 14.6 B. P. H. into the reboiler of the raw cracked naphtha stabilizer to which the raw cracked naphtha was fed at the same rate as in the previous run, namely, at about 208 B. P. H. The following were the conditions and results of the run:

Overhead gas from stabilizer accumulator drum B. P. H.	7.14	2.99

From the above, it will be noted that with substantially the same high pressure steam supply to the stabilizer reboiler and substantially the same reboiler vapor temperature, and with approximately the same cooling water temperature for the stabilizer overhead condenser, very material advantages were secured with the butane recycle and injection into the reboiler of the stabilizer. Thus, the percentage of available butylenes left in the stabilizer bottoms dropped from approximately 38% to 23%, while the percentage of available butanes left in the bottoms was increased from approximately 37% to 38%, and the Reid vapor pressure of the stabilized bottoms was maintained or even slightly increased from 10.1 to 10.5 pounds. Moreover, the percentage of available butylenes in the feed to the polymerization unit was increased from approximately 46.5% to 54% while the percentage of available saturated butanes decreased from approximately 55.5% to 47.5%. At the same time, there was a substantially increased condensation of the stabilizer overhead and consequently an increase in the charge to the polymerization unit, as is shown by the drop in the overhead gas from the accumulator drum from 7.14 to 2.99 barrels per hour.

It is thus seen that, by the method of the present invention, the raw cracked naphtha was stabilized to desired volatility and Reid vapor pressure while at the same time a substantially improved separation between saturated butanes and unsaturated butylenes was secured so that a greater proportion of the saturated butanes remained in the stabilized cracked naphtha while a greater proportion of the unsaturated butylenes was removed overhead, condensed and thus recovered for the polymerization feed. These beneficial results were secured solely by recycling the available butane fraction from the polymer debutanizer to the stabilizer reboiler, and without otherwise altering the conditions of operation including high pressure steam supply to the reboiler or temperature of cooling water to the stabilizer overhead condenser.

While the invention has been described above in connection with a polymerization unit, it is to be understood that the invention is also applicable to other conversion processes for converting low-boiling or normally gaseous hydrocarbons to high octane gasoline hydrocarbons suitable for aviation fuel. Likewise, while the invention has been described in connection with

the stabilization of raw cracked naphtha to obtain a separation between saturated butanes and unsaturated butylenes, it is to be understood that the invention is also applicable to effecting a desired separation between pentanes and amylenes, hexanes and hexylenes, etc.

Referring to Fig. 2, the invention is shown as applied to the stabilization of raw cracked naphtha and natural gasoline and the alkylation of isobutane with C₄ and C₅ olefins to thereby materially increase the yields of aviation gasoline from available charge stocks. As shown, raw cracked naphtha from a conventional cracking unit is introduced by line 60 to stabilizer 61 equipped with reboiler 62, and operated to take overhead by line 63 a C₅ and lighter fraction containing a substantial proportion of the C₅ olefins. A stabilized cracked naphtha containing a substantial proportion of normal pentane for volatility is withdrawn as bottoms by line 64. The overhead fraction is passed through condenser 65 to accumulator 66. Condensate is forced by pump 67 in part through line 68 to serve as reflux in tower 61, and in part by line 69 to a depropanizer 70. In the latter, the charge is fractionated to remove overhead through line 71 C₃ and lighter, and obtain a bottoms cut consisting essentially of C₄ and C₅ which is passed by pump 72 through line 73 to a conventional alkylation unit 74.

While any conventional alkylation process can be employed, the invention is described for purposes of illustration in connection with a sulfuric acid alkylation step. In this process, an additional supply of isobutane introduced by the recycle line 75 to be hereinafter further described, or from any other suitable source, is mixed with the olefinic C₄-C₅ charge from line 73 in the presence of strong sulfuric acid of about 88-100% concentration at temperatures of about 35-70° F. and under sufficient pressure to maintain the hydrocarbon in liquid phase. Any conventional type of unit, such as the well known pump and time tank reactor, the jet reactor, or the mixer of the turbo type can be used. The isobutane is maintained in substantial molar excess of the olefins; and preferably the operation is of the well known emulsion recycle type in which contact ratios of from 50:1 up to 200:1 or higher are employed. Under these conditions, the isobutane is alkylated by the C₄ and C₅ olefins to produce good yields of gasoline hydrocarbons or alkylate of high anti-knock value. It is to be understood that other well known alkylation catalysts, such as hydrofluoric acid, aluminum chloride-hydrocarbon complex, BF₃-water complex, and the like can be used; although strong sulfuric acid is preferred for this operation. As the alkylation unit per se forms no part of the present claimed invention, further description thereof is unnecessary. It is understood that in conventional practice, a stream of the reaction products is withdrawn to a suitable settler where the catalyst is separated from the hydrocarbons, and the latter are then neutralized before being passed to the stabilizing and fractionating equipment. These various steps and the equipment therefor are well known, and it is to be understood that the diagrammatic illustration of the alkylation unit represented by the numeral 74 includes the alkylation reactor, settler and neutralizer.

The neutralized hydrocarbon reaction products from the alkylation unit are passed by line 75 to a debutanizer 78 where unreacted C₄ hy-

drocarbons consisting essentially of excess isobutane and normal butane are removed overhead by line 79 and a debutanized alkylate is withdrawn as bottoms by line 80. As the alkylation reaction consumes the olefins in the charge, the overhead C₄ stream is further fractionated in a butane fractionator 80' where an isobutane cut is removed overhead and recycled by line 75 to the alkylation unit while a normal butane stream is removed as bottoms by line 81 and passed in whole or part by pump 82 through line 83 to the stabilized cracked naphtha in line 64 to increase the yield and volatility of the motor gasoline.

The debutanized alkylate withdrawn by line 89 is passed by pump 85 through a line 86 to a depentanizer 87 where C₅ is removed by the overhead line and depentanized alkylate is removed as bottoms by line 89. It is to be understood that the above-described order of towers can be changed. For example, the raw alkylate can first be depentanized, and the resulting C₅ and lighter offgases fractionated in a series of towers to obtain the various fractions described, including an isobutane cut, a normal butane cut, an isopentane cut and a normal pentane cut. The C₅ overhead fraction consisting essentially of isopentane and normal pentane is mixed with a stream of debutanized natural gasoline introduced by line 90, and the mixture passed into a de-isopentanizer 91. The latter is operated to remove isopentane overhead by line 92, and the de-isopentanized natural gasoline containing the normal pentane from the alkylate is removed as bottoms by line 93. The latter is passed by pump 94 to a depentanizer 95 where normal pentane is removed overhead by line 96 and the depentanized natural gasoline discharged as bottoms by line 97. It is to be understood that the fractionating towers 70, 78, 80', 87 and 91 are equipped with the usual reboilers or other heating means for the base of the towers, and with suitable condensers and accumulators for the overhead and pumps for supplying condensate as reflux to the tops of the towers as well as forcing the remaining portion of the condensate to the next tower or unit in series, which elements are not shown for simplicity in illustration.

The overhead normal pentane fraction passes by line 96 to condenser 99 and thence by rundown line 100 to accumulator 101 from which condensate is withdrawn through line 102 by pump 103 and forced in part through reflux line 104 to the top of tower 95, and in part by recycle line 105 to the reboiler 62 of the cracked naphtha stabilizer 61. In this manner, a saturated C₅ stream consisting largely of normal pentane is provided for injection into stabilizer 61 to thereby obtain a more complete separation of C₅ olefins in the overhead, while retaining a desired proportion of normal pentane in the stabilized cracked naphtha bottoms. While the above described introduction of debutanized natural gasoline into the fractionating system is advantageous for the production of more isopentane, it is to be understood that this is not essential in accomplishing the broader objects of the present invention. For example, the C₅ cut from the stabilization of the alkylate may be directly fractionated into isopentane and normal pentane fractions, without addition of any natural gasoline cut.

The depentanized alkylate removed from tower 87 by line 89 is forced by pump 107 through line 108 to the alkylate fractionator where a desired aviation gasoline fraction boiling up to about 350-375° F. is removed overhead by line 110 and

alkylate bottoms are discharged by line 111 and forced by pump 112 through line 113 to storage or for further treatment. Preferably, the alkylate bottoms are passed by line 113 to suitable blending tanks (not shown) where they are mixed with the stabilized cracked naphtha from line 64 to increase the yield of motor gasoline. The overhead aviation fraction is condensed in condenser 115 and passed through rundown line 116 to accumulator 117 from which the aviation gasoline is discharged by line 118 to storage or for further treatment. The overhead isopentane fraction from line 92 is passed to suitable condenser and accumulator equipment (not shown) and the condensate blended with the aviation gasoline from line 118 to thereby increase the yield and adjust the volatility of the aviation gasoline. It is to be understood that the depentanized natural gasoline from line 97 may, if desired, be passed to a further fractionating tower (not shown) serving as a de-isohexanizer from which an overhead isohexane cut may be obtained for blending with the aviation gasoline from line 118 to further increase the yield thereof. The resulting natural gasoline bottoms from this further fractionating operation may then be passed to reforming or other treatment, or may be blended directly with the stabilized cracked naphtha from line 64 for motor gasoline.

It is to be understood that the debutanized natural gasoline introduced by line 90 has been previously stabilized to separate C₄'s and lighter, and the offgases from this stabilization fractionated to separate an isobutane-rich fraction which is introduced by line 120 into the isobutane feed for the alkylation unit 14 to thereby serve as an external source of supply of additional isobutane. A normal butane also recovered from the natural gasoline in this latter operation may be added to the normal butane stream passed by line 83 to the stabilized cracked naphtha in line 64. These elements are not illustrated in the drawing for the sake of simplicity in illustration.

While the invention has been described above in combination with a suitable polymerization or alkylation unit, from which the desired recycle stream is obtained for injection into the cracked naphtha stabilizer, it is to be understood that the invention is not limited to these particular catalytic conversion units. Thus, it is obvious that the stabilization method described herein can be applied in conjunction with other catalytic or thermal conversion units, such as isomerization, cyclization and aromatization, and various combinations of these with polymerization and alkylation. Likewise, the invention is not limited to the stabilization of cracked naphtha and natural or straightrun gasoline fractions, since the particular stabilization and fractionation method is more broadly applicable to the distillation of olefin and paraffin containing hydrocarbon mixtures generally.

The invention can also be employed in a stabilizing operation where the overhead condensate capacity is insufficient for normal operation, to thereby enable the stabilizer to operate at a higher pressure for the same reboiler temperature, with resultant increased condensation of the overhead at the higher pressure with the same condenser cooling surface. Likewise, the invention can be applied to stabilizing operations where difficulty is encountered due to the temperature of available cooling water for the overhead condensate being too high, since the higher stabilizer pressures resulting from the hydrocar-

11

bon injection permit increased overhead condensation with the higher temperature cooling water.

Obviously many modifications and variations of the invention, as hereinbefore set forth, may be made without departing from the spirit and scope thereof, and therefore only such limitations should be made as are indicated in the appended claim.

I claim:

The method in the stabilization of a raw cracked naphtha, and the manufacture of gasoline hydrocarbons of high anti-knock value from the overhead of the stabilizing operation, wherein the C₄ hydrocarbons of the raw cracked naphtha consist of substantial proportions each of isobutane, normal butane, isobutylene, butylene-1 and butylene-2, and the proportion of the butylene-2 in said C₄ fraction is roughly equivalent to the combined proportion of isobutylene and butylene-1, which comprises introducing the raw cracked naphtha into an intermediate portion of a stabilization and rectification zone, heating the lower portion of said zone to vaporize C₄ and lighter constituents by indirect heat exchange with a heating medium, subjecting the overhead from said zone to cooling and condensation at the pressure of said zone by indirect heat exchange with a cooling medium, returning a portion of the resulting condensate as reflux to an upper portion of said zone, the operation being such that a portion of the C₄ together with lighter constituents passes overhead from said zone while a stabilized cracked naphtha containing sufficient C₄ to meet volatility specifications is discharged as bottoms, subjecting another portion of said overhead condensate to catalytic conversion to largely convert butylenes thereof into high anti-knock gasoline hydrocarbons while n-butane of said overhead condensate remains inert, separating from the products of said catalytic conversion said gasoline hydrocarbons, also separating from the products of said catalytic conversion a C₄ fraction consisting mainly of n-butane, and recycling said C₄ fraction consisting mainly of n-butane to the interior of said stabilization and rectification

12

zone in sufficient proportion in relation to the raw cracked naphtha feed to accomplish the following three results, namely (1) materially increase the pressure in said zone for a given temperature in the lower portion of said zone, (2) materially increase the condensation of overhead vapors from said zone for a given temperature of the cooling medium supplied thereto, and (3) materially increase the combined proportion of isobutylene, butylene-1 and butylene-2 taken overhead for a given retention of C₄ including n-butane in the stabilized cracked naphtha bottoms to meet volatility specifications.

LOREN P. SCOVILLE.
